(57) CLAIM

The ornamental design for a parasol handle, as shown and described.

DESCRIPTION

FIG. 1 is a perspective view of a parasol handle showing my new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIGS. 1; and,

FIG. 7 is a bottom view of FIG. 1.

The broken line portions of the parasol handle in FIGS. 1-7 represent portions of the parasol handle and form no part of the claimed design.

1 Claim, 6 Drawing Sheets
